UNITED STATES PATENT OFFICE.

JOHN F. MACKAY, OF TRENTON, NEW JERSEY.

BROODER.

1,103,887.

Specification of Letters Patent. Patented July 14, 1914.

Application filed June 17, 1913. Serial No. 774,149.

To all whom it may concern:

Be it known that I, JOHN F. MACKAY, a citizen of the United States, residing at Trenton, in the county of Mercer and State of New Jersey, have invented new and useful Improvements in Brooders, of which the following is a specification.

This invention relates to brooders for raising incubator hatched chicks, and the principal object of the invention is to produce a simple and efficient colony brooder suitable for use either in doors or in the open and which will accommodate and safely care for a large number of chicks.

15 One object of the invention is to simplify and improve the heating apparatus, a coal stove or heater being employed.

A further object of the invention is to simplify and improve the means whereby the heat is regulated.

20 A further object of the invention is to produce a coal-burning brooder-heating apparatus to which fuel may be fed from the top without disturbing the brooder.

25 With these and other ends in view which will readily appear as the nature of the invention is better understood, the same consists in the improved construction and novel arrangement and combination of parts 30 which will be hereinafter fully described and particularly pointed out in the claims.

In the accompanying drawing has been illustrated a simple and preferred form of the invention, it being, however, understood 35 that no limitation is necessarily made to the precise structural details therein exhibited, but that changes, alterations and modifications within the scope of the claims may be resorted to when desired.

40 In the drawing,—Figure 1 is a side elevation, partly in section, of a device constructed in accordance with the invention. Fig. 2 is a top plan view of the same.

45 Corresponding parts in the several figures are denoted by like characters of reference.

The heater of the improved brooder consists of a stove or furnace A of which 5 designates the fire box, 6, the grate, and 7, the ash pit for which a draft door 8 is provided, said door being hinged at its upper edge, as shown, so that it will naturally 50 gravitate to a closed position. The stove body, which has been shown as tapering upwardly, is provided at its upper end with a

hopper B, the discharge opening of which, 55 is adapted to constitute a seat for a valve or damper 10. The hopper B, the upper portion of which flares beyond the stove body, is provided with a top plate 11 having an opening covered by a lid 12 which is 60 located directly above the discharge opening 9 of the hopper. The lid 12 is apertured for the passage of the stem 13 that extends upwardly from the valve or damper 10. The top plate has an opening 14 which is located 65 at one side thereof substantially in vertical alignment with the draft door 8; a valve or damper 15 whereby said opening may be obstructed is hinged adjacent to the outer edge of the opening, said damper being provided with an outwardly extending arm 16. A flue 17 for carrying off the products of combustion is mounted on the top plate 11.

Fulcrumed on a support 18 which rises from the top plate 11 is a lever 19, one arm 75 of which is connected with the valve stem 13 and with one end of a flexible element 20, which latter is connected at its lower end with the damper 8 and intermediate its ends with the arm 16; the other arm of the lever 80 19 carries a counterweight 21 for approximately balancing the valves 10, 15 and 8. The parts are so arranged that when the door or valve 8 is wide open, the valve 15 will be seated, and the valve 10 will, likewise, be wide open to permit products of combustion to pass from the fire box to the exit flue 17. As the valves 8 and 10 move in the direction of their respective seats the check valve or damper 15 will gradually be 90 unseated.

A thermostat 21' is supported on a bracket 22 extending from the stove body, said thermostat including a rod 23 which is guided through an aperture 24 in a portion 95 of the top plate 11 which overhangs the stove body. The rod 23 is connected with the arm of the lever 19 that carries the counterweight 21 by means of an intermediate lever 26 fulcrumed on the upright 100 18 and a connecting member 28, said lever and connecting member being introduced for the purpose of increasing the movement of the lever 19 relatively to that of the rod 23, thereby rendering the operation of the 105 device more effective.

The top plate 11 supports a downwardly flaring hood D which for convenience may

be composed of hingedly connected members 29, 30, one of which may, furthermore, be provided with a door 31 through which access may be conveniently had to the interior for the purpose of removing ashes from the ash pit 7 and the like. A curtain 32 of flexible material depends from the lower edge of the hood D and terminates a short distance above the ground so as to afford ample protection while not hindering the ingress and egress of the chicks.

The operation and advantages of this invention will be readily understood from the foregoing description taken in connection with the drawings. Coal may be conveniently fed to the stove by manipulating the lever 19 so as to raise the valve 10 to a non-obstructing position and then sliding the lid 12 upwardly upon the valve stem; the fuel may then be introduced and will be guided over the downwardly inclined walls of the hopper through the aperture 9 and into the fire box. The valves or dampers will be automatically operated to regulate the draft so as to maintain the temperature evenly at a predetermined degree. The general construction is simple, inexpensive and thoroughly efficient for the purpose for which it is provided.

30 A thermometer 35 is provided to enable the temperature within the hood to be ascertained; and the hood may have a hand hole, 36, through which the thermometer is accessible.

35 It will be seen that the top plate covering the hopper extends laterally beyond the perimeter thereof all around the heater. This is a decidedly advantageous arrangement in a heater for a brooder, as it permits 40 a hood of simple truncated cone form like that illustrated to be easily applied to and supported by the said plate, no particular fitting and shaping of the parts with reference to each other being necessary to secure

45 practically air-tight joints when they are united. It will also be observed that the means by which the draft controlling dampers, 8 and 15, and the closure 10, are controlled—the levers 19, 26, etc.—are supported by the said top plate, thus making a self-contained apparatus, or one supported by a single base. The check draft opening 14 is in the top plate and hence exposed, so that when the damper 15 is open the air taken in 50 to check the draft is drawn from the open, and not from within the hood D, so that the temperature within the latter is not lowered by the inflow of outside air when the check damper is opened. Furthermore, by making the heater with an opening in its top through which fuel may be fed to the fire chamber, and applying the hood so that it surrounds the heater but does not cover the top, I am enabled to practically use a coal

65 or other solid fuel burner as the heater for

a brooder and to replenish the fire with fuel from time to time as occasion requires, without having to open the brooder chamber, with the incident disadvantage of the loss of heat and danger from the confined air being contaminated by the escaping gases of combustion. 70

Having thus described the invention, what is claimed as new, is:—

1. A heater for brooders having a fire box, 75 a hopper disposed above and communicating with the fire box, a top plate covering the hopper and extending beyond the perimeter thereof entirely around the heater, dampers for controlling the draft of the 80 heater, and means for controlling the dampers supported by the top plate of the hopper.

2. A heater for brooders having a fire box, 85 a hopper disposed above and communicating with the fire box, a top plate covering the hopper and extending laterally beyond the perimeter thereof entirely around the heater, a closure controlling communication between the hopper and fire box, dampers 90 for controlling the draft of the heater, and means for controlling the movements of the closure and the dampers supported by the top plate of the hopper.

3. A heater for brooders having a fire box, 95 a hopper disposed above and communicating with the fire box, a top plate covering the hopper and extending beyond the perimeter thereof entirely around the heater, there being a check draft opening through the top 100 plate into the hopper, a damper for controlling the draft through said opening, a damper controlling the draft to the fire box, a closure controlling the communication between the hopper and fire box, and a single 105 means supported on the said top plate and connecting respectively with the said dampers and closure, by which their movements are controlled.

4. The combination of a heater for burning solid fuel, provided with a top perforated to permit fuel to be fed through it to the fire chamber of the heater, means carried by the heater for supporting a brooder hood, and a suspended hood supported by 110 the said means so as to be free from the surface on which the heater rests and forming a brooder chamber surrounding the heater. 115

5. The combination of a heater for burning solid fuel, having a chamber in its upper 120 portion covered by a top through which is a fuel feed opening, a flue through which the products of combustion pass off communicating with the said chamber, a valve controlling the communication between the said 125 chamber and the fire box of the heater, means for operating said valve supported by the heater, means carried by the heater for supporting a brooder hood, and a suspended hood supported by the said means so 130

as to be free from the surface on which the heater rests and forming a brooder chamber surrounding the same.

6. The combination of a heater for burning solid fuel having a feed opening through its top, means carried by the heater for supporting a brooder hood, and a suspended hood supported by the said means so as to be free from the surface on which the heater rests and forming a brooder chamber surrounding the heater, the top of the hood being open so as to leave exposed the top of the heater, thereby permitting access to the fuel feed opening therein without disturbing the hood.

7. The combination of a heater for burning solid fuel, provided with a top perforated to permit fuel to be fed through it to the fire chamber of the heater, the top extending laterally beyond the heater, and a

hood supported from the edge of the top and forming a brooder chamber entirely surrounding the heater.

8. The combination of a heater adapted to burn solid fuel, having a top perforated to permit fuel to be fed through it to the fire chamber, and perforated also to form a check draft opening, a hood supported by the heater and extending downward from the said top to enclose a brooder chamber, and a damper for the said check draft opening by which the draft through the same may be controlled.

In testimony whereof I affix my signature in presence of two witnesses.

JOHN F. MACKAY.
